UNITED STATES PATENT OFFICE.

EDWIN NAHR, OF LONG BEACH, CALIFORNIA.

HANDLE CONNECTION.

1,142,837.

Specification of Letters Patent. Patented June 15, 1915.

Application filed April 10, 1914. Serial No. 830,883.

To all whom it may concern:

Be it known that I, EDWIN NAHR, a citizen of the United States, and a resident of Long Beach, in the county of Los Angeles and 5 State of California, have invented a new and Improved Handle Connection, of which the following is a full, clear, and exact description.

My invention relates to a mop or equivalent article the mop head and handle of 10 which are equipped with novel co-acting bearing elements to effect an adjustable connection of the handle with the head.

The invention will be particularly explained in the specific description following.

Reference is to be had to the accompanying drawings forming a part of this specification, in which similar characters of reference indicate corresponding parts in all the 20 views.

Figure 1 is a front view of a mop embodying my invention, parts of the handle being broken away; Fig. 2 is a side elevation; Fig. 3 is a longitudinal sectional elevation; Fig. 25 4 is a transverse sectional elevation; Fig. 5 is a plan view of the mop head, the handle being omitted; and Fig. 6 is a plan view of the fastener for the mop pad.

In constructing a practical embodiment of 30 my invention in accordance with the illustrated example, a cap or case 10 is provided, adapted to receive the upper end of the mop pad 11, which is secured to the casing in the manner hereinafter described. The bearing members of the handle comprise sockets here 35 shown as consisting of spaced angle plates 12, having the feet 13 thereof secured to the top of the case 10 by rivets 14 or equivalent holding means. The sockets 12 are formed 40 with registering bearings 15, and the socket 16 for the handle 17 has expansible bearing elements rockable in the bearings 15 and frictionally held therein.

The bearing members on the socket 16 are 45 in the form of an expansible T-head comprising members 18 and 19. The members 18 are rigid with the socket 16 and project laterally at each side to enter the rigid bearings 15 on the case 10. The member 19 extends transversely from side to side into 50 the bearing 15, and is disposed oppositely to the members 18. Both the rigid members 18 and the movable member 19 are rounded exteriorly to conform to the curvature of the 55 fixed bearing member 15 on the case.

In order to hold the bearing members 18,

19, of the handle in such frictional contact with the bearings 15 as to maintain the handle in any adjusted position, but yet sufficiently yielding as to permit the handle to be forcibly swung through an angle for adjusting its position, a spring 20 is interposed between the members 18, 19, so that the latter are held expanded under the influence of said spring. As here shown, the 60 spring is coiled about a pin 21 that projects forwardly from the socket 16 centrally of the bearing members 18, and extends through an aperture 19^a in the movable bearing member 19, the opposed ends of the 65 spring thus pressing against the respective bearings 18, 19, and tending to force them outwardly into frictional contact with the bearings 15.

By the described construction it will be 70 seen that the handle may be given various angular positions relatively to the mop head and the handle will be maintained in the adjusted position, the spring 20 being sufficient to prevent accidental displacement of the 75 handle.

In the top of the case 10 a depression or shallow well 22 may be formed at the approximate center of said case, and an orifice 23 in the case at the bottom of said well 80 leads to the interior of the case to a distributing absorbent pad 24. The said pad 24 lies against the top of the case at the under side, and is held in position by a fastener 25 which secures the upper end of the 85 mop pad 11. The pad and the means to oil the same are not claimed in the present application.

The fastener 25 may consist of two resilient sections, as shown in Fig. 6. The sections are so connected as to permit of the fastener being compressed laterally against the resiliency of the sections, and also the said sections may have rockable movement 90 relatively to each other, the connections serving to facilitate the entrance of the fastener into the case 10. I have shown the sections as each formed at one end with an eye 26 embracing the adjacent terminal of the opposite section, said adjacent terminal 100 having a bent end 27 constituting a stop limiting the lateral expansion of the sections. The fastener 25 is placed in the interior of the pad 11, at the top, the material of the pad being gathered above said fastener, 105 and the bunched top of the pad with the fastener therein is inserted within the lower 110

open end of the case or cap 10, said open bottom of the cap or case being defined by an inwardly projecting flange 10^a. The end of the pad is crowded between the flange 10^a and the under side of the oil pad 24, and the fastener 25 expands within the case above the flange 10^a, thereby holding the mop pad securely in position in contact with the oil pad 24.

10 The described means for securing the mop are not herein claimed.

As seen best in Fig. 5, the cap 10 is of oval form, being approximately elliptical, and thereby is adapted for effective use beneath furniture and in corners.

Having thus described my invention, I claim as new and desire to secure by Letters Patent:

1. In a device of the character described, 20 a head having a bearing with its axis substantially parallel to the surface to be acted upon, and a handle member having a transverse expansible bearing thereon received in the bearing of the head and rockable in the latter bearing.

2. In a device of the character described, a head having a bearing with its axis substantially parallel to the surface to be acted upon, a handle member having a transverse

extensible bearing thereon formed of separable members received in the bearing of the head and rockable in the latter bearing.

3. In a device of the character described, a head having a bearing, a rockable handle member having opposed expansible bearing elements received in the bearing of the head, and an interposed spring between said expansive elements and serving to press the same into holding frictional engagement with the bearing of the head.

4. In a device of the character described, a head, having a bearing presenting spaced socket members, a handle member having a bearing conforming to said socket members and composed of a rounded member fixed to the handle and an opposed movable rounded member, a pin projecting from the fixed member through the movable member, and a spring coiled about said pin and abutting against said fixed and movable members.

In testimony whereof I have signed my name to this specification in the presence of two subscribing witnesses.

EDWIN NAHR.
